UNITED STATES PATENT OFFICE.

ANDREW MELLECK, OF BRADDOCK, PENNSYLVANIA.

COLLAPSIBLE CONTAINER.

1,116,460.

Specification of Letters Patent. Patented Nov. 10, 1914.

Application filed November 19, 1913. Serial No. 801,766.

To all whom it may concern:

Be it known that I, ANDREW MELLECK, a citizen of the United States, and residing in the borough of Braddock, in the county of Allegheny and State of Pennsylvania, have invented or discovered new and useful Improvements in Collapsible Containers, of which the following is a specification.

My invention consists in new and useful improvements in collapsible cases and other containers. Such articles are intended to be extended for containing or shipping goods and to be collapsed when stored or returned.

15 The box or container comprises a bottom to which the end pieces are hinged and to which are secured the fixed side-bases or lower portions of the sides, the upper portions of the sides being hinged to said bases. When collapsed, the ends fold inwardly upon the bottom and the sides fold down upon the ends. The lid is hinged to the top edge of one of the sides. By making the base of one side higher than the base of the other side, the side having the lower base folds down upon the ends and the other side folds down upon said first named side. The lid is hinged to the side having the lower base so that it may be folded between the 30 two sides when the box is collapsed.

I also provide a new and improved corner construction for a collapsible box whereby the latter may be held securely in its extended position and all danger of collapse upon the goods contained in the box is avoided.

I also provide new and improved means for latching or securing the lid when the box is extended.

40 In the accompanying drawings, Figure 1 is a perspective showing a box, embodying my improvements, extended, ready to receive goods; Fig. 2 is a plan view of the same, the lid being swung back out of the way; Fig. 3 is an enlarged end view of the box collapsed; Fig. 4 is an enlarged detail view in section along the line IV-IV in Fig. 2; Fig. 5 is an enlarged detail of the dowel pin structure used, and Fig. 6 is a 50 broken front view of the box showing the lid latch.

The following is a detailed description of the drawings:

A is the bottom provided with transverse stiffening cleats 1 attached to the under face thereof at its ends.

B-B are the two ends hinged, as at 2, to the bottom A and folding down flat upon the said bottom when the box is collapsed. The two sides are marked C and D. The side C is hinged to a base C' which is rigidly secured to the side edge of the bottom A and the top face of the cleats 1. The height of the base C' is sufficient to permit the side C to fold down on the collapsed ends B, as shown in Fig. 3. The side D is hinged to a fixed base D' which is secured to the opposite edge of the bottom A and to the top faces of cleats 1. The hinges which secure said sides to their bases are marked 3 and the lower straps thereof are preferably of sufficient length to be bent angularly and secured to the bottom A, as shown in Fig. 1. The lid E is hinged as at 4 to the top edge of side C. The base D' of side D is of sufficient height to permit the side D to be folded down upon the side C and the lid E when the two latter are folded as shown in Fig. 3. It is thus evident that ends B rest upon the bottom A, the side C' rests upon the ends B, the lid E rests upon the side C and the side D rests upon the lid E when the box is collapsed.

The side C is provided with vertical strengthening cleats 5 which are in alignment with and abut against similar cleats 6 on the base C' when the side C is extended, thus giving a firmer bracing to the side. Likewise the side D is provided with similar cleats 7 which abut against similar cleats 8 on the base D' when said side is extended. The ends B are preferably provided with horizontal top and bottom cleats 9 and 10, respectively.

The top edges of the ends B are provided with a plurality of dowel pins 11 which fit into holes 12 in the lid E to hold the lid in place and enable it to brace the box when the latter is extended. Said dowel pins are preferably provided in pairs and may be formed integrally by rolling up the prolonged ends of a metal plate 13 and securing said plate by means of a screw or screws 15 between the top cleat 9 and the outer face of end B, as shown in Figs. 4 and 5, the pins 11 extending upwardly to engage the holes 12 in the lid E.

To brace the sides C and D and hold the same in place, when the box is extended, I provide hinges 16, one of whose straps is secured to the outer face and top edge of each side and whose other strap is adapted

- 2
- to be swung over and lie upon the top edges of the ends B when the box is extended. Said last named strap is provided with perforations 17 which engage the pins 11 thus preventing the collapse of the ends and sides. The cover fits down over said perforated hinge-straps, preventing the disengagement of the said straps from the dowel-pins. To permit the collapse of the box, said perforated straps are swung up out of engagement with said dowel-pins, thus permitting the separation of the ends and sides of the box. However, when the lid is in place said straps are maintained in their operative position and can not be accidentally loosened from said pins. When the lid is lifted, the engagement of the perforated hinge-straps with said dowel-pins holds the box extended for the introduction or removal of goods.
- 20 The latch or fastening device comprises a hinged hasp 18 secured to the free edge of the lid E and having a longitudinal slot 19 intersected by a cross slot 20.
- 21 is a plate secured to the outer face of side D and provided with a vertical loop 22 which is adapted to extend through the slot 19.
- 23 is a ring mounted on the loop 22 and adapted to slip through the cross-slot 20 and fall down to the bottom of loop 22 below said cross slot.
- It is evident that the hasp 18 can not be released from the loop 22 until the ring 23 is raised by hand to register with and pass through the cross-slot 20.
- 24 is a perforation in the lower end of hasp 18 to accommodate the wire of a seal which may also pass through the loop 22 and the slot 19.
- 40 Where it is desired to secure the box against unauthorized opening, a padlock may be applied to the loop 22.
- The form of latch shown provides an in-

expensive yet very effective fastening device which takes up but little space and 45 does not interfere with the folding of the crate into a small space.

What I desire to claim is:—

1. A corner fastener for a collapsible container, said container being composed of 50 a plurality of elements in hinged relationship and one of said elements being provided with holes in its face adjacent to a second element, said fastener comprising a metal plate secured to the face of said second element and having its edges extended and formed as integral pins adapted to engage said holes, and a perforated plate hinged to a third element adapted to be engaged by said pins and to be interposed between the two first named elements, substantially as and for the purpose set forth. 55
2. A corner fastener for a collapsible container, said container being composed of a plurality of elements in hinged relationship and one of said elements being provided with holes in its face adjacent to a second element, said fastener comprising a metal plate secured to the face of said second element and having its edges extended 60 and formed as integral pins adapted to engage said holes, a metal plate secured to the outer face of a third element and to the edge of said element, and a perforated plate hinged to said last named plate, said perforated plate being interposed between said 65 first and second named element and engaged by said pins, substantially as and for the purpose set forth. 70

Signed at Pittsburgh, Penna., this 17th 80 day of November, 1913.

ANDREW MELLECK.
